UNITED STATES PATENT OFFICE.

SAMUEL M. GROSSMAN, OF CHICAGO, ILLINOIS.

METHOD OF MAKING FINGER RINGS.

Application filed February 14, 1921. Serial No. 444,683.

To all whom it may concern:

Be it known that I, SAMUEL M. GROSSMAN, a citizen of the United States, residing at Chicago, in the county of Cook and State 5 of Illinois, have invented new and useful Improvements in Method of Making Finger Rings, of which the following is a specification.

This invention relates to finger rings, and 10 more particularly wedding rings, and the method of making the same.

One object of my invention is to make the ring of two separate annular parts, one being relatively thicker than the other and 15 constituting the body of the ring, and the other part being in the form of a relatively thin ornamental band fitted tightly in an outwardly opening channel in the ring body with the band fitting between the side flanges 20 of the channel and being substantially flush with the outer surface of the ring body on opposite sides of the channel.

Another object of the invention is to have 25 the ornamental band fit tightly in the channel without the use of solder, this being accomplished by varying the diameter of the ring body and band relatively to each other after the band has been applied in the channel, thus holding the band against circumferential movement with respect to the ring 30 body.

A further object of my invention is to cut 35 out the side edges of the band to conform to the design on which the band is fashioned so that the bottom of the channel may be visible on opposite sides of the band, and thus furnish a background for the band and set off the same, especially when the ring 40 body is made of one color, say green gold, and the band is made of a contrasting color, as for instance white gold.

Other and further objects of the invention will appear from the following specification, taken in connection with the accompanying 45 drawings, in which—

Fig. 1 is a perspective view of a finger ring made in accordance with my invention;

Figs. 2 to 5 inclusive illustrate the respective steps followed in making the ring by 50 the method of my invention;

Fig. 6 is an enlarged fragmentary top plan view of the ring shown in the preceding figures after the ring body and band have been fitted together; and

Fig. 7 is an enlarged side elevational view 55 of a ring, with a portion in section, showing

an ornamental band applied in the channel in the side of the ring, as well as around the outer circumference of the same.

The finger ring of my invention is made in 60 two separate annular parts 1 and 2, the former being relatively thicker than the latter and constituting the body of the ring. As shown in the drawings, the ring body 1 is provided with an outwardly opening channel 3 extending completely about the outside of the ring body and having side flanges 4, 65 annular in form and projecting radially outward substantially the same distance.

The other or outer part 2 of the ring is 70 in the form of a relatively thin annular band having a width to fit in the channel 3 between the side flanges 4 thereof, and a diameter, when first made, slightly greater than that of the bottom of the channel, as 75 shown in Fig. 3. The outer surface of the band 2 may be chased or carved to give it any desired ornamental and artistic design, and its side edges are cut in conformity with the design on which the band is fashioned. 80

After the parts 1 and 2 have been made separately and given annular form, as shown in Fig. 2, the band 2 is forced over one of the flanges 4 until it is in the channel 3 and surrounding the ring body 1, as illustrated 85 in Fig. 3. At this time, the band 2 is slightly larger in diameter than the channel 3 and one part may slip circumferentially about the other. The next step in my method is to make the two parts fit tightly against 90 each other without the use of solder to hold them against circumferential movement. This is accomplished by inserting the ring body 1 on a tapered mandrel 5 as shown in Fig. 4 and driving the mandrel to expand the 95 ring body 1 radially outward against the ornamental band 2 and cause it to fit tight in the channel 3. The full effect of this expansion may be gained by inserting the mandrel 5 through a hole in an anvil 6 with the ring 100 resting thereon, as shown in Fig. 5. The upper end of the mandrel 5 is tapped with a hammer or mallet 7, shown in dotted lines in said Fig. 5, to expand the ring body 1 to the extent required. After this has been 105 done, the edges of the ring body 1 may be filed or otherwise finished to be made smooth, and the whole polished and buffed to give it a proper and desired finish and luster.

As shown in Fig. 6, portions of the band 110 2 extend across the channel 3 and engage against the side flanges 4 thereof. This holds

the band 2 against lateral displacement in the channel. The side edges of the band between such portions, being cut out or carved to conform to the design on which the band 5 is fashioned, terminate short of said flanges, and thus expose to view portions of the bottom of the channel 3 on opposite sides of the band. This has a dual purpose. First, it allows the contour of the design of the band 10 at its sides to be readily observed and be set out, and, second, the bottom of the channel being polished and having a luster forms a background for the ornamental band to set it off with a pleasing and ornate effect. 15 This effect is further accentuated when the ring body 1 and band 2 are made of metals having contrasting colors, as for instance the ring body 1 of green gold and the band 2 of white gold. Should solder be used to 20 secure the parts together, the bottom of the channel would not form a background for the band, because the solder on fusing would run beyond the side edges of the band and substantially, if not wholly, fill the spaces 25 mentioned.

In Fig. 7, I have shown an ornamental band 7 applied in an annular channel 8 in one side of a ring body 1^a. These parts are fitted together by expanding the ring 30 body, in the same manner as shown in the preceding figures and as heretofore described. Applied about this ring body 1^a is an ornamental band 2^a, the same as before. The ring shown in Fig. 7 is thus provided with two ornamental bands, one on 35 one side and the other about the ring. A third band could be employed by fitting the same in a channel on the opposite side of the ring.

40 The ring of my invention is especially applicable as a wedding ring, as the bands may be made in varied designs, now ordinarily chased on wedding rings.

While I have shown and described herein 45 in detail a finger ring of my invention and

the method by which it is made, it is to be of course understood that the details shown and described may be variously changed and modified without departing from the spirit and scope of my invention.

50

I claim as my invention:

1. The method of making a finger ring, consisting in, first, making the ring in two separate annular parts, one constituting the body of the ring, and the other the ornamental band therefor, second, providing the ring body with an annular channel having side flanges, third, applying the band in the channel between said flanges, and, fourth, causing the band to fit tight in the channel 55 in the ring body by varying the diameter of one with respect to the other.

2. The method of making a finger ring, consisting in, first, making the ring in two separate annular parts, one constituting the 60 body of the ring and the other the ornamental band therefor, second, providing said ring body with an annular channel extending about the outer circumference of the same and having side flanges, third, forcing 65 said band over one of said side flanges into said channel, and, fourth, causing the band to fit tight against the bottom of said channel by varying the diameter of the band and ring body relatively to each other.

75 3. The method of making a finger ring, consisting in, first, making the ring in two separate annular parts, one constituting the body of the ring and the other the ornamental band therefor, second, providing said 80 ring body with an annular channel extending about the outer circumference of the same and having side flanges, third, forcing said band over one of said side flanges into said channel, and, fourth, expanding the 85 ring body into tight contact with the band.

In testimony that I claim the foregoing as my invention, I affix my signature this 8th day of February, A. D. 1921.

SAMUEL M. GROSSMAN.
